UNITED STATES PATENT OFFICE.

GEORGE E. PALMER, OF CEDAR RAPIDS, IOWA.

IRONING-BOARD.

SPECIFICATION forming part of Letters Patent No. 358,748, dated March 1, 1887.

Application filed May 20, 1886. Serial No. 202,709. (No model.)

To all whom it may concern:

Be it known that I, GEORGE E. PALMER, a citizen of the United States, residing at Cedar Rapids, in the county of Linn and State of 5 Iowa, have invented certain new and useful Improvements in Ironing-Boards, of which the following is a specification.

The object of my invention is to improve the construction of ironing-boards and the 10 supporting-frame thereof, and particularly to so construct the apparatus as to adapt it to the uses of a step-ladder.

The invention consists in the novel construction, arrangement, and adaptation of the 15 parts of the device to the ends sought, as hereinafter set forth and claimed.

In the accompanying drawings, forming a part of this specification, Figure 1 represents a side elevation of the invention, and Fig. 2 20 a view, of the same, in perspective as a step-ladder.

Similar letters of reference indicate corresponding parts.

Near what may be considered the lower end 25 of the board A, and to the under side thereof, is attached a cleat, c, nearly as long as the width of the board. To each end of the cleat is pivoted by means of screws one of a pair of legs, B. These are made nearly or quite as 30 long as the board, are stayed by suitable rungs, and, for the sake of greater strength and stability, are preferably flared at the bottom, as shown. Upon the middle rung of this pair of legs is pivoted another pair, C, one 35 end of which corresponds nearly with the width of the longer pair, and the other end converges and joins, as represented. The object of this is to give the greatest degree of stiffness to the legs and the broadest floor- 40 bearing with the least material. These legs are similarly stayed by rungs. As will be evident, the legs are adapted to fold up close to the board when not in use.

About in the middle of the bottom of the 45 board is attached a notched block, b, with which the upper end of the legs C engage, and

by means of which any desired adjustment in the height of the board may be made. A cleat, a, serves to prevent the warping of the upper end of the board and as a stop for the 50 legs C at the point of extreme depression. A cord, d, connects the stop b with the legs C, for a purpose hereinafter explained.

To the upper rung of the legs B is pivoted a board, e. When it is desired to use the apparatus as a step-ladder, the legs are set in the 55 position shown in Fig. 2, and this board is turned down on the longest rung of the legs C, when a hole, i, in its under side engages with a pin or screw in the rung and locks the 60 parts together. The lower parts of the device are spread apart, as shown, the distance being limited by the length of the cord d, and thus forms a convenient step-ladder, the successive rungs affording suitable steps, and the 65 board e a final landing. When not thus in use, the board e is folded back between the legs, as indicated by the dotted lines in Fig. 2, and fastened by a suitable button, o.

The result of this construction and arrangement is a strong, convenient, and easily-adjustable ironing-board, which is at the same time adapted to serve as a step-ladder. 70

Having thus briefly described my invention, what I claim as new, and desire to secure by 75 Letters Patent, is—

The combination of the ironing-board A, legs B, having the step-board e, provided with the hole i, and pivoted to the upper rung of the legs B, the legs C, pivoted to the middle rung 80 of said legs B, with a pin on the longer rung engaging with the hole in the step-board, and the cord d, connecting said legs C with the board A, all substantially as and for the purpose set forth.

In testimony whereof I affix my signature in presence of two witnesses.

GEO. E. PALMER.
